UNITED STATES PATENT OFFICE.

JAMES DIXON AND THOMAS DIXON, OF BARNOLDSWICK, ENGLAND.

MOP AND THE LIKE.

Application filed May 29, 1923, Serial No. 642,273, and in Great Britain October 24, 1922.

This invention has reference to mops and the like and has for its object to provide improved means of securing the heads or equivalent thereof to their handles.

5 According to this invention the material forming the head or equivalent of a mop or the like is looped through the bight or eye or hook of a U hook or similarly shaped member and is clamped therein against the 10 end of the handle or a fitting thereon by the tightening up of said member by means of a nut or equivalent.

In the accompanying drawings Figs. 1 and 2 are elevations at right angles to each 15 other of a mop handle provided with one form of means constructed in accordance with the invention, for securing the mop head. Fig. 3 is a view similar to Fig. 1 partly in section, and Fig. 4 is a sectional 20 view looking at the end of the handle.

Referring to the drawings, the mop handle 5 has mounted on it a metal sleeve 6, provided at its outer end with an annular flange 7 in which are formed diametrically opposite holes 8 (see Fig. 3). The sleeve 6 is formed on its interior surface with tapered longitudinal ribs 9 (Fig. 4) of V section which bite into the handle when the sleeve is driven thereon from the end and prevent 30 the sleeve from rotating. The sleeve may be further secured by one or more screws 10.

Through the holes 8 pass the limbs 11 of a U-shaped member 12. The limbs 11 lie in longitudinal grooves 13 in the sleeve 6 so as to be flush with the exterior thereof, and have their extremities 14 bent at right angles to co-act with the convolutions of a stout spiral spring 15 which is rotatably and slidably mounted on the sleeve 6, and thrusts 40 against the flange 7 and so serves as a cam or nut to tighten up the U-shaped member 12, by drawing its bight towards the end of the handle 5, and to slacken the member and move the bight thereof, or allow same 45 to be drawn, away from the end of the handle.

Pieces of cloth or other material to form the mop head are looped through the bight of the member 12 which is then tightened up by means of the spring 15 during its rotation to firmly clamp the material against the end of the handle.

What we claim as our invention and desire to secure by Letters Patent is:—

55 1. A mop comprising a handle having an abutment at the end thereof, a clamping

member carried by the handle for movement toward and from the end thereof for clamping to the end the cleaning elements to be used, said member having a tongue projecting therefrom, and a helical spring rotatable on the handle and against said abutment, said tongue engaging with a turn of the spring so as to be resiliently cammed thereby, upon rotation of the spring, in a direction to draw the clamping member toward the end of the handle for resiliently anchoring the cleaning elements thereto.

2. A mop comprising a handle stick, a sleeve secured to an end of the handle and having upon its outer end a flange, a helical spring surrounding the sleeve and rotatable thereon against the end face of the flange, a U-shaped clamping member disposed upon the outer face of the flange and having its arms passing through the flange and supported for sliding movement lengthwise of the handle stick, said U-shaped member having the free ends of its arms bent to form tongues engaging between the turns of the helical spring so as to be cammed resiliently by the spring during the latter's rotation in a direction to resiliently draw the U-shaped member toward the flange to clamp between said flange and member the cleaning elements.

3. A mop comprising a handle stick, a sleeve secured upon one end thereof and having at its outer end a peripheral flange, a clamping member disposed at the outer face of the flange and having arms extending to the opposite face of the flange and along the sleeve so as to be guided for reciprocation lengthwise of the stick, said arms having lateral tongues thereon, a cam member rotatably mounted upon the sleeve and having a thrust engagement with the inner face of the flange and also having a cam surface running in a direction spirally and from end to end axially, said cam surface engaging with the tongues to draw the clamping member toward the flange when the cam member is rotated.

4. A mop comprising a handle stick, a sleeve secured to one end thereof and having a peripheral flange, a U-shaped clamping member at the outer end of the sleeve with its arms passing to the opposite face of the flange and along the sleeve, said sleeve having on its outer periphery longitudinally extending slots in which the arms of the clamping member are guided in a direction

lengthwise of the sleeve, and a controlling member rotatably mounted on the sleeve and having a thrust against the inner face of the flange and acting upon the arms that pass along the sleeve to cam the latter lengthwise of the stick when the controlling member is rotated, whereby the clamping

member will be drawn toward the end of the stick to anchor the cleaning elements thereto.

10

In witness whereof we have hereunto set our hands.

JAMES DIXON.
THOMAS DIXON.
